UNITED STATES PATENT OFFICE.

WALTER LOEBEL, OF LEIPZIG, AND KUNO FRANZ, OF FRANKFORT-ON-THE-MAIN,
GERMANY.

PROCESS OF AND APPARATUS FOR MIXING POWDERED SUBSTANCES OR HIGHLY- CONCENTRATED SOLUTIONS WITH A LIQUID OR DISSOLVING THEM IN THE LATTER.

1,098,811.

Specification of Letters Patent.

Patented June 2, 1914.

Application filed December 11, 1911. Serial No. 665,117.

To all whom it may concern:

Be it known that we, WALTER LOEBEL, engineer, and KUNO FRANZ, chemist citizens of the Empire of Germany, residing at 5 Leipzig and Frankfort-on-the-Main, Germany, respectively, have invented certain new and useful improvements in processes of and apparatus for mixing powdered substances or highly-concentrated solutions with 10 a liquid or dissolving them in the latter, of which the following is a specification.

For the purpose of thoroughly mixing powdered substances with liquids, or for dissolving them therein, there are now used 5 various forms of mechanical agitating-apparatus. These have however the drawback that the substances to be mixed or dissolved deposit on the agitators, which must be thoroughly cleaned whenever there is to be treated, in the same apparatus, another different substance which it is not permissible to contaminate with the one previously treated. Furthermore, some substances thus treated tend to float on the surface of the liquid, requiring a complicated construction of the agitator. Now, in order to avoid these drawbacks which, especially when the substances to be treated are often changed, cause great inconvenience and unnecessary expense, we proceed according to our present invention in the following manner: We use a mixing-jet (nozzle) for thoroughly mixing the respective substance and liquid, which may be worked, as required, either by steam, or by the liquid itself, put under a certain pressure. In order to mix in the powdered substances floating on the surface of the liquid, it is important to place the aspirating side of the mixing-jet at the level of the surface of the liquid or near to it, the delivery jet acting in a downward direction. Thus a thorough circulation of the liquid and of the substance to be dissolved is obtained. Especially, the jet, acting downward, causes a strong whirling of the liquid near the bottom of the vessel. We either arrange the mixing-jet so that it can be elevated and lowered, or, in case of a stationary mixing-jet, we so construct the vessel in which the mixing or solution is to be effected that it can be elevated or lowered relative to the mixing-jet. For this purpose, the vessel may be placed on a table the posi-

tion of which can be adjusted as required in each case, by a suitable device.

The object of the above-mentioned arrangements is to adjust the level of the liquid to such a height toward the sucking-port of the mixing-jet that there is always obtained the best possible whirling movement. By this arrangement it is also possible to use vessels of any size, and thus to adapt them in each special case to the requirements of the manufacture.

It is advantageous to use a vessel with a spherical bottom, which facilitates the circulation of the liquid.

In cases where heat must be applied for mixing and dissolving, there may be used as the motive-fluid of the mixing-jet, either steam, or the liquid itself, which for that purpose is put under pressure and, if required, heated. In cases which do not permit the heating of the liquid, there is used for the working of the mixing-jet the liquid itself, in combination with a pump and at a suitable temperature.

The preferred apparatus is shown in the accompanying drawing, in which the figure is a side elevation with the mixing-vessel in section.

The vessel 1, having a concave bottom 2, is supported by legs 3 on a vertically-adjustable table 4. This table is carried by cylindrical standards 5, 5', which are arranged to slide vertically in fixed tubes 6. The lower portion of the central standard 5' has a thread 7 receiving a bevel-gear nut 8, driven by another bevel-gear 9 through a shaft 10, sprocket-chain 11 and wheel 12, and crank 13. The jet-pump, which is arranged in the upper part of the vessel 1, comprises a conical nozzle 14, which is the lower end of a steam-supply pipe 15, and a concentric conoidal casing, or converging-diverging combining tube, 16 having inlet ports 17. Pipe 15 is connected by a flexible pipe 18 to a fixed pipe 19 having a control-valve 20. Pipe 15 carries a rack 21, actuated by a pinion 22 and hand-wheel 23, for adjusting the position of the jet-pump, which is normally arranged with its inlets 17 substantially at the surface 24 of the body of liquid in the vessel. When steam or other motive-fluid under pressure is supplied through pipe 15, the powdered floating or other substance to

be mixed or dissolved is drawn, with portions of the liquid, into the ports 17 and the mixture is forcibly jetted downward into the body of liquid. A vigorous circulation and mixing is thereby effected, the lines of flow being indicated in a general manner by the arrows.

The invention is applicable to the mixing both of powdered substances and highly-concentrated solutions with liquids, either to produce a permanent mixture or emulsion, or a solution.

Having now particularly described our invention, what we claim is:

1. The process of mixing substances with a liquid or dissolving them therein, which consists in repeatedly drawing the substance and liquid from near the surface of a body of the liquid, and jetting them vertically downward into the body of the liquid.

2. The process of mixing substances with a liquid or dissolving them therein, which consists in repeatedly drawing the substance and liquid along converging lines from near the surface of a body of the liquid, and jetting them vertically downward into the body of the liquid.

3. Apparatus for mixing substances with a liquid or dissolving them therein, comprising a vessel for holding a body of the liquid, and a jet-pump vertically mounted in said vessel, said jet-pump constructed and arranged to draw the substance and liquid from near the surface of the liquid and to jet them downward into the body of the same.

4. Apparatus for mixing substances with a liquid or dissolving them therein, comprising a vessel for holding a body of the liquid,

ing a vessel for holding a body of the liquid, and a jet-pump axially mounted in said vessel, said jet-pump constructed and arranged to draw the substance and liquid from near the surface of the liquid and to jet them vertically downward into the body of the liquid, said jet-pump and vessel being relatively vertically adjustable.

5. Apparatus for mixing substances with a liquid or dissolving them therein, comprising a vessel for holding a body of the liquid, and a jet-pump vertically mounted in said vessel, said jet-pump provided with a converging-diverging combining tube, and constructed and arranged to draw the substance and liquid from near the surface of the liquid and to jet them vertically downward into the body of the same.

6. Apparatus for mixing substances with a liquid or dissolving them therein, comprising a cylindrical vessel for holding a body of the liquid, said vessel having a concave bottom, a jet-pump vertically mounted in the axis of said vessel, said jet-pump constructed and arranged to draw the substance and liquid from near the surface of the liquid, and to jet them vertically downward into the body of the same.

In testimony whereof, we affix our signatures in presence of two witnesses.

WALTER LOEBEL.
KUNO FRANZ.
